C. A. GLASS

TANK

Filed April 7, 1924

UNITED STATES PATENT OFFICE.

CLIFTON A. GLASS, OF KANSAS CITY, MISSOURI.

TANK.

Application filed April 7, 1924. Serial No. 704,666.

This invention relates to oil tanks such as are used for storing oil in the oil fields. It relates primarily to a floating deck or cover to rest or float upon the surface of the oil so as 5 to close off atmospheric air from contact with the oil and thereby prevent evaporation of the lighter hydrocarbon constituents of the oil. The cover will be hereinafter referred to as a floating deck to conform to the nomenclature of the oil industry.

Floating decks have been provided prior to my invention, but my invention consists in providing a deck formed from fabric supported upon floats, preferably made of lumber and fastened thereto, the advantage being that the deck can be shipped in a "knock down" compact manner and it can readily be set up in the old fields without requiring special tools or equipment.

20 The novel construction of the invention will be referred to hereinafter, reference being had to the accompanying drawings in which

Fig. 1 is a vertical longitudinal sectional view through a tank with which my invention is associated.

Fig. 2 is a perspective view of the deck showing the construction for the accommodation of a swing pipe, and

30 Fig. 3 is a fragmentary sectional view of a slightly modified form of deck.

The tank is shown as consisting of a vertical wall 1, a bottom 2 and a roof 3. The roof may be of relatively light construction, since it need not be air tight but it should be of such construction that it will shed snow, rain and the like. The roof is shown as supported upon vertical posts or stanchions 4 in the upper ends of which are rafters 5 upon which the roof rests. The roof has a gauge hole or opening 6 of usual construction and the roof may be provided with a breather pipe 7 if desired. The floating deck consists of a sheet or sheets of fabric 8 fastened to floats 9 which preferably consist of wooden beams of lumber 10. The deck should have an area substantially equal to the cross sectional area of the tank and the edges of the deck may be notched at 11 to clear the uprights 12.

50 The fabric of the deck is shown as provided with a slit 13 reenforced by braces 14 and 15 to permit the cable 16 for the swing pipe 17 to pass through as will be clearly seen in Figs. 1 and 2. The small surface of the oil which will be exposed to atmosphere by

reason of the slit will not be appreciable so practically no evaporation will take place on account of the exposed surface of the oil through the slit. The fabric of the deck is provided with a plurality of openings 18 to 60 permit the uprights to extend through the fabric, the openings 18 being reenforced by bracing members 19. The fabric may consist of any suitable material which will not be readily attacked by petroleum or petroleum derivatives and inasmuch as I am able to buy such fabric on the open market, I do not make any special claim for the fabric itself, the invention consisting rather in the adaptation of a suitable fabric to a relatively light supporting frame so as to close off communication between the oil in the tank and atmosphere and thus eliminate liability of evaporation losses.

In Fig. 3 I have shown a slightly modified 75 form of deck in which the floats 20 illustrated as lumber, rectangular in cross section are provided with a top fabric 21 and a lower fabric 22 to make a box-like float or deck, the edges of the fabrics 21 and 22 being secured 80 to the edge of the lumber structure by overlapping the ends 23 and 24 and fastening the same by nails or similar devices 25.

It will be apparent that the invention may be shipped from the factory in a collapsed 85 compact manner and set up for use in the oil field and when set up, the deck will have an opening 26 in line with the gauge hole 6 so that the gauger may have access to the oil within the tank.

What I claim and desire to secure by Letters-Patent is:—

1. In combination with an oil tank, a floatable deck comprising an open floatable frame including a circumferential skirt, and a cover impermeable to vapor extending across said frame for support thereby above the surface of contents of the tank.

2. In combination with an oil tank, a deck comprising an open frame adapted to float on contents of the tank and including laterally spaced floatable members, and a cover secured to one of the surfaces of the frame for support thereby.

3. In a deck for oil tanks, an open framework comprising beam-like members for floating on contents of the tank, laterally spaced floatable members connected with the frame and defining an opening, and a fabric cover secured to the upper surface of the 110

frame and to said floatable members for support thereby and having an opening registering with said first named opening.

4. In combination with a liquid-containing tank, a flexible cover substantially co-extensive with the cross section of the tank and having an opening, and a frame for supporting the cover from the liquid comprising lat-

erally spaced beams adapted to float on the liquid, and beam-like members secured to said cover and defining said opening and adapted to float on the liquid for supporting the edges of the cover adjacent said opening. 10

In testimony whereof I affix my signature.

CLIFTON A. GLASS.
